UNITED STATES PATENT OFFICE

ADOLPH T. SCHMIDT, OF MILWAUKEE, WISCONSIN, ASSIGNOR TO LINDEMANN & HOVERSON COMPANY, OF MILWAUKEE, WISCONSIN, A CORPORATION OF WISCONSIN

TEMPERATURE CONTROL FOR GAS RANGES

Application filed August 14, 1931. Serial No. 557,041.

The present improvements relate, in general, to gas ranges and more particularly to temperature regulating means for gas range ovens, although they are also of general application and may be employed to control the fuel supply to other burners under various conditions.

A primary object of the improvements, among others, is to provide a novel and efficient heat regulator for ovens which is certain in operation, may be readily set and can be easily adjusted and calibrated.

A further object is to provide an improved temperature control having a simplified construction which lends itself to a setting on the side or front of the range.

Other objects of the improvements will be apparent upon reference to the accompanying specification and drawings, in which

Fig. 1 is a front elevation of a fragment of a gas range oven, showing one form of the improved temperature control, partly in section and elevation;

Fig. 2 is a side elevation of the oven illustrated in Fig. 1, showing the improvements partly in section and partly in elevation, certain parts being omitted or broken away;

Fig. 3 is a rear elevation of a modified form, certain parts being in section;

Fig. 4 is a side elevation of the structure illustrated in Fig. 3.

Referring to the drawings, only a fragment of the oven 5 of the range is shown in Fig. 1. Conventional elements comprise the top 6, inner wall 7, outer side wall 8, fuel supply pipe 9 and oven burner 10. Interposed in the pipe 9, is a valve casing 11 wherein the passage of fuel is regulated, as will hereinafter appear. The passage of the main body of fuel through casing 11 to the main burner 10 is controlled by disk valve 12, while the pilot burner receives fuel through pipe 13 which communicates with casing 11 through port 14 controlled by adjusting screw 15. A port 16, controlled by adjusting screw 17, by-passes main valve 12, so that a small amount of fuel may be supplied to burner 10, even though the supply is cut off by the closing of valve 12.

A valve rod 18 is housed in tubing 19 which

extends from the valve casing 11 to bracket 20. This tubing not only serves to protect the rod 18, but also maintains a definite distance between the valve 12 and the thermal element. The lower end of rod 18 engages 55 a valve rod extension member 21 which in turn is connected to valve 12.

A pin or rod 22 is loosely mounted in the upper end of bracket 20, in spaced relation to the upper end of rod 18. A heavy gauge 60 thermostatic metal strip 23, bent into U-shape, is loosely held in place between the pin 22 and the upper end of rod 18, whereby the latter is actuated by the thermal element, in response to rise in temperature. As illustrated in Fig. 1, the thermal element 23 and rod 18, are holding the valve 12 open, against the energy of a coil spring 24 which is provided for constantly urging the valve in closing direction.

Means for adjusting the position of the thermal element and the parts movable therewith are provided in the pin operating lever 25 and screw member 26 engaging same. Said screw is advanced or retracted by hand wheel 27 which is secured in place by screw 28, while a temperature dial 29 is clamped between member 27 and a collar 30 on screw 26. The dial may be rotated to bring various temperature readings opposite indicator 31 and is held in any such position by the energy of spring 32 engaging collar 30.

When the oven is cool and not in use, the temperature control is in the position illustrated in Fig. 1. In this position, the thermostatic member 23 is holding the valve 12 open, against the energy of spring 24. Due to the dial setting, both these members 23 and 24 are tensioned, so that the energy of each is urging the valve in opposite directions. As illustrated, these opposed forces however, are balanced with the valve in open position. When either force preponderates, the valve is moved in a corresponding direction until the forces become balanced again.

In use, the main valve 33 controlling fuel to the oven (see Fig. 2) is opened and the oven burner lighted. The dial may be set to any desired reading and as the oven 5 heats up, the thermal element 23 contracts,

causing the ends of the U-shaped member to come closer together, whereby the valve 12 is moved in closing direction by the energy of spring 24. The flame at the burner is accordingly not as intense due to the smaller supply of fuel, whence the member 23 may cool and expand, thus opening the valve to admit more fuel. This regulation may transpire until the temperature, for which the device is set, is attained. It is manifest that the opening of the valve is inversely proportional to the degree of temperature experienced by the element 23.

When the oven temperature has reached the temperature set on the dial, the thermal element 23 has contracted sufficiently to permit spring 24 to close valve 12. However, a minimum flame is maintained on burner 10, by having screw 17 open, thereby allowing sufficient fuel through the by-pass 16, so that the burner never entirely goes out. A small flame is therefore present, when the valve 12 opens due to slight cooling of the oven below the temperature for which the device was set, so that the oven may be readily and immediately heated up again to the proper temperature. However, in case the flame is extinguished, the pilot light supplied with fuel through pipe 13, is continuously burning and will relight the burner 10 when valve 12 opens again after cooling of the oven. Manifestly, any variation in the temperature of the oven causes the position of the thermal member 23 to change so that the valve 12 will open or close to maintain the desired temperature in the oven. When it is desired to discontinue use of the oven, the cock 33 may be closed and the burner extinguished, whereupon the thermal member expands on cooling and returns valve 12 to the open position illustrated in Fig. 1, where it remains until again used.

In case the actual temperature of the oven does not coincide with that indicated on the dial 29, the screw 28 may be loosened and the dial rotated until the correct reading is opposite the pointer 31, whence the screw may be fastened and the dial clamped tightly in place by wheel 27. The remaining temperatures may then be calibrated on the dial, which will then be found to be accurate for use with the selected thermal element. Under conditions of use, the thermal element 23 may be placed under greater or less tension by manipulating screw 26 through dial 29. This causes lever 25 to move pin 22 whence the ends of member 23 are brought closer together or moved away from each other, as the case may be. Such adjustments increase or diminish the movement of the thermal element in response to the heat, necessary to cause closing of the valve.

It will be understood that the parts 18 and 19 have been broken off for convenience in illustration so as to condense the show-

ing, but they are of sufficient extent to reach from the upper to the lower portion of the oven as more clearly seen in the embodiment in Fig. 3.

While the improvements just described are mounted for use at the side of a range, the modified form is adapted for use on the front thereof. Referring to the embodiment of Figs. 3 and 4, the fuel supply conduit 39 is provided with a valve casing 41, having a pilot burner tube 43, a valve 42 and a by-pass 46. Fuel to the pilot burner is controlled by screw 45, while the by-pass is provided with adjustable screw 47. The protecting tube 49, rods 48, 51, bracket 50, thermal element 53, and pin 52 are similar to the elements illustrated in the first embodiment. Supported above the pin 52, is a lever 55 pivoted at 56 which carries a lever 57, one end of which engages pin 52 with the other end engaging a pin 58 mounted in bracket 50. A cam 59 engages pin 58 and has an operating lever 60 extending forwardly through the front wall 61 of the oven, where it terminates in a pointer 62. A dial housing 63 and dial 64 are provided on the front wall, the dial being graduated with temperature readings. Upon reference to Fig. 3, one end of lever 55 is engaged by adjusting screw 65, which rocks the lever about fulcrum 56, thereby elevating or lowering the fulcrum of lever 57.

The operation of this form is similar to that earlier described. The lever 60 and pointer 62 are set to the desired temperature, the movement of which causes cam 59 to move thermal element 53 through pins 58 and 52 and lever 57. The mechanism thereafter functions to regulate the heat of the oven in the manner already described. In case the actual temperature does not coincide with that of the dial and pointer, an adjustment may be made by moving adjusting screw 65 whereby the position of lever 57 may be altered. In this manner, the temperature control may be conveniently calibrated.

While the disclosed embodiments are preferable it is apparent that various elements may be modified. For example, rods 18-21 may be provided in one piece, instead of being separate. Various other modifications, within the scope of the present improvements, may be made without departing from the purview of the invention.

I claim:

1. The combination with an oven burner, of a fuel supply conduit therefor, a normally open valve in said conduit, a rod operatively connected with said valve, an adjustable pin spaced from said rod, a thermostatic element adapted to be tensioned; mounted on said rod and pin a spring member urging said valve closed, and means for actuating said pin for tensioning or untensioning said element.

2. The combination with an oven burner, of a fuel supply conduit therefor, a normally

- open valve in said conduit, a rod operatively connected with said valve, an adjustable pin spaced from said rod, a thermostatic element adapted to be tensioned; mounted on said rod and pin, a spring member urging said valve closed, an adjustable member engaging said pin, and a cam member for actuating said pin through said member for tensioning and untensioning said element. 5
- 10 3. The combination with an oven burner, of a fuel supply conduit therefor, a normally open valve in said conduit, a rod operatively connected with said valve, an adjustable pin spaced from said rod, a thermostatic element adapted to be tensioned; mounted on said rod and pin, a spring member urging said valve closed, an adjustable lever engaging said pin and a cam member for actuating said pin through said lever for tensioning and untensioning said element. 15
- 15 4. The combination with an oven burner, of a fuel supply conduit therefor, a normally open valve in said conduit, a rod operatively connected with said valve, an adjustable pin spaced from said rod, a thermostatic element adapted to be tensioned; mounted on said rod and pin, a spring member urging said valve closed, a second movable pin, an adjustable lever engaging both pins and a cam member for actuating said second pin whereby said thermostatic element may be tensioned or untensioned. 20
- 25 5. A heat regulating device including an oven, a burner therefor, a fuel supply pipe for said burner, a valve casing and disc valve disposed in said pipe for controlling the flow of fuel, a spring urging said valve closed, a bowed thermostatic element adapted to be tensioned for holding said valve open 30 against the action of said spring in the cool position of said element, said element re- 35
- leasing its pressure against said valve in response to rise in temperature whereby said spring may be effective for closing same, the construction and arrangement being such, that the degree of opening of said valve is inversely proportional to the degree of heat experienced, a movable pin upon which one end of said thermostatic element is supported, and a movable indicator member for adjusting said pin and element. 40
6. A heat regulating device comprising a burner, a fuel supply pipe therefor, a valve casing in said pipe, a valve therein, said casing having a fuel port for conveying fuel to a pilot burner and a passage by-passing said valve, spring means urging said valve in closing direction and a U-shaped thermal element normally holding said valve open against the action of said spring, said element being adapted to be tensioned for holding said valve open against the action of said spring means. 45
7. A heat regulating device including a burner, a fuel supply pipe for said burner, a valve casing and a valve disposed in said pipe for controlling the flow of fuel, a spring urging said valve closed, a rod engaging said valve, a slidable pin substantially aligned with said rod and spaced therefrom a U-shaped thermal and spring element having its free ends engaging and supported by said rod and pin, a second movable pin spaced laterally of said first pin, a lever disposed between said pins and engaging both, an eccentric engaging said second pin and a manually operable arm secured to said eccentric whereby movement of said eccentric is transmitted to said U-shaped element for tensioning same and concurrently opening said valve. 50
